UNITED STATES PATENT OFFICE.

GEORGE MCADAMS, OF WINCHESTER, INDIANA.

STOVE-PIPE SHELF AND STOVE-LID HOLDER.

SPECIFICATION forming part of Letters Patent No. 255,441, dated March 28, 1882.

Application filed November 5, 1881. (No model.)

To all whom it may concern:

Be it known that I, GEORGE MCADAMS, a citizen of the United States, residing at Winchester, in the county of Randolph and State of Indiana, have invented a new and useful Stove-Pipe Shelf and Lid-Holder, of which the following is a specification.

The object of my improvement is to provide a cheap attachment to stove-pipes which will, 10 in addition to the ordinary uses of a stove-pipe shelf, serve also as a holder for the stove-lids when removed from the stove, and support them in a horizontal position, thereby admitting of culinary implements being placed over 15 them.

Referring to the accompanying drawing, the hoop A may be made of a suitable size to support large-sized lids, the smaller sizes fitting inside; or it may be made large enough to 20 close all sizes, as many notches or recesses a being made in the supports b b b as there are different sizes to be accommodated. The seg- 25 mental parts c c form, in connection with the lugs d d d, headless threaded rods e e, and thumb-nuts f f f f, an adjustable collar which

may be applied to any of the different sizes of stove-pipes in common use. The braces g g firmly connect hoop A with collar, and also serve to strengthen the same when subjected to strain, as it is liable to be. 30

What I claim as my invention, and desire to secure by Letters Patent, is—

1. The combination, in a stove-pipe shelf and lid-holder, of the hoop A with supports b b b, having recesses a a a, substantially as 35 described.

2. In a stove-pipe shelf and stove-lid holder, the combination of the hoop A, having supports b b b and recesses a a a, with seg- 40 mental parts c c, provided with lugs d d d, threaded rods e e, and thumb-nuts f f f f, for the purpose specified.

3. The combination of the hoop A, having supports b b b, with braces g g and adjustable collar, as set forth.

GEORGE MCADAMS.
